AWNING

Arthur Chrosnik, Chicago, Ill.

Application September 25, 1948, Serial No. 51,131

6 Claims. (Cl. 20—57.5)

1

This invention relates to improvements in awnings and more particularly to window awnings although adapted also for other applications. One object is to provide an awning that is easy of operation, noiseless and that will regulate the admission of light and exclude rain. A further object is to provide an awning of the louver type that may be operated from inside or outside the house or other structure to which applied and one wherein an adjustment to admit any desired light will retain its adjusted position until released.

A further object is to provide an awning having louvers that may be individually removed, reversed in case of warp and one that will shed outwardly such water as may fall thereupon and that is devoid of water pockets. A further object is to provide an awning that is positive and efficient in operation, inexpensive to manufacture, readily applied to or removed from a window or other surface, that is easily cleaned, painted or sprayed and one wherein all parts are so accessible as to be readily reached for repair or replacement when necessary.

My invention resides in the arrangement and combination of parts and in the details of construction described in the specification and particularly pointed out in the appended claims. It is understood that I do not limit myself to the precise embodiment of the invention shown herewith as various changes may be made within the scope of what is claimed without departing from the spirit of the invention. I intend no limitations other than those imposed by the claims.

In the drawing:

Fig. 1 is a view in perspective of awnings embodying my invention and showing the louvers both open and closed and illustrating its application to a residence or similar structure.

Fig. 2 is a detail sectional view, enlarged, on the line 2—2 of Fig. 1.

Fig. 3 is a detail sectional view similar to Fig. 2 but showing a slightly modified structure.

Fig. 4 is a detail sectional view taken on the line 4—4 of Fig. 1.

Fig. 5 is a fragmentary view of Fig. 4, enlarged.

Fig. 6 is a fragmentary face view of Fig. 4 with parts broken away.

Fig. 7 is a fragmentary view of a slightly modified form of Fig. 2, and

Fig. 8 is a view of Fig. 3 but with adjustable parts in an altered position.

The reference numeral 1 denotes a portion of a structure to the windows of which the awning may be applied. Suitably secured to an over-

2

hang 2 of the structure are the spaced outwardly and downwardly disposed parallel hangers 3 preferably covered with some suitable material such as a weather protecting fabric or the like. Referring now to all figures except Figs. 3, 7 and 8 the hangers 3 are further supported by braces 4, 4' secured to the face of the structure or to the window casings, the hangers and braces forming the awning framework, the terminal braces being preferably wider than the intermediate ones.

Pivotedly secured to adjacent hangers 3 upon pins 5 are the louvers 6 that extend from hanger to hanger and that overlap in closed position and that in open position may be spaced apart to a greater or lesser degree depending upon the angle of the louver so that light as desired may be admitted through the louvers and through the window protected by the awning. The louvers between any two hangers form a unit and are adapted for operation independently of any other unit of the awning assembly, the louvers spaced from their hangers by the anti-friction collars 3a.

The two terminal louvers of a set, one at the top and one at the bottom of each unit are each connected by a hinge 7 to an actuating bar 8 which bar is formed along its outer longitudinal edge with notches 9 at spaced intervals, said notches spaced apart by riser portions 10, said notches receiving the inner longitudinal edges of the louvers to form a friction hinge connection therewith, the risers between notches being inclined to keep the louvers seated in the notches. The space between adjacent notches is substantially equal to their distance from the hanger in the wide open position of the louvers clearly shown in Fig. 4 so that in their closed position, shown in Fig. 2, they rest upon and overlap each other.

Secured to the inner longitudinal edge, which is a straight edge, of the actuating bar 8 by the hinge 11 is the sectional lift elbow 12, the meeting sections thereof connected by the hinge 13, said elbow connected by the hinge 14 to the structure 1. Extending through a slot in the lift elbow 12 is the lift cord 15 that beneath the elbow is knotted as at 16 to prevent withdrawal of the cord, said cord passing about a small sheave 17 secured to overhang 2 and to and about the shaft of a spool 18 that extends through the window casing or wall and within the structure terminates in or is integral with the ratchet 19 having handle 20 for rotating the spool manually to wind the cord thereupon. With the cord partially unwound from the spool and the lift elbow sections 55 angularly disposed or partially folded substan-

tially as shown at Fig. 4 the louvers are wide open to admit the maximum light and air. To close them the spool is manually rotated to wind the cord thereupon until the lift elbow is fully extended and the louvers folded upon each other into closed position as shown in Fig. 2. The ratchet will releasably retain the movable parts in any intermediate position in well known manner. Instead of the spool and ratchet the cord 15 may pass from the sheave 17 to and be wound about the post 21 secured to a wall of the structure or to the window casing.

Referring now to Figs. 3 and 8 a slightly modified form is shown wherein a rod 22 connected by hinge 23 to the structure 1 is slotted to permit passage therethrough of the cord 24 knotted at one end and that passes over sheave 25 and is secured to the anchor 26 fast to structure 1. A roller 27 at the free end of the rod 22 bears against the elbow lift to raise same from angular to extended position. When the cord is unwound from the anchor the lift elbow with actuating bar will move downwardly and the louvers to open position by gravity. The scalloped drop 29 is provided for ornamentation. A cushioned stop block 30 depending from the overhang in the path of movement of the topmost louver may be gently engaged thereby or will be contiguous thereto at the end of the forward or closing movement of that louver.

What is claimed is:

1. In an awning, downwardly and outwardly disposed hangers, louvers pivotally connected to said hangers, said louvers in one position overlapping each other, an actuating bar hinged at its ends to upper and lower terminal louvers, said actuating bar notched along one edge in a manner to receive and permit rotation in said bar notches of edges of the intermediate louvers, a sectional lift elbow hinged to said actuating bar, and means engaging said lift elbow for moving its sections upon their common hinge.

2. In an awning, downwardly and outwardly disposed hangers, louvers pivotally connected to said hangers, an actuating bar, hinges connecting said actuating bar to certain of said louvers, one edge of said actuating bar being notched, said notched portions separated by riser portions, said bar notched portions constructed to receive and permit rotation of one edge of each of the remaining louvers, an elbow lift, an elbow lift hinge connecting said elbow lift to said actuating bar, and means for adjusting said elbow lift, said means including a cord secured to said elbow lift.

3. In an awning, downwardly and outwardly disposed hangers, louvers pivotally connected to said hangers, an actuating bar hinged to certain of said louvers, said actuating bar notched along one edge in a manner to receive and permit rota-

tion in said bar notches of one edge of each of the remaining louvers, a lift elbow hinged to said actuating bar, a hinged rod, a roller carried thereby engaging said lift elbow, and means for moving said rod upon its hinge, together with said lift elbow, and locking same in adjusted positions, said means including a cord secured to said rod and extending through said lift elbow.

4. In an awning, downwardly and outwardly disposed hangers, louvers adjustably connected to said hangers, an actuating bar hinged to terminal louvers having notched portions constructed to receive and permit rotation of the edges of certain of said louvers, a lift elbow hinge connected at one end to said actuating bar, and means for adjusting said elbow lift, said means including a cord secured to said elbow lift.

5. In an awning in combination with a support having an overhang, downwardly and outwardly disposed hangers secured to the overhang, braces connecting said hangers to the support, louvers pivotally connected to said hangers, said louvers in one position overlapping each other, an actuating bar, hinges connecting terminal louvers with the ends of said actuating bar, friction hinge connection between one edge of each of the intermediate louvers and said actuating bar, and means for adjusting said actuating bar relative to said braces.

30 6. In an awning in combination with a support having an overhang, downwardly and outwardly disposed hangers secured to the overhang, braces connecting said hangers to the support, louvers pivotally connected to said hangers, 35 said louvers in one position overlapping each other, an actuating bar, hinges connecting terminal louvers with the ends of said actuating bar, friction hinge connection between one edge of each of the intermediate louvers and said actuating bar, an elbow lift connecting said actuating bar and the support, a sheave carried by the overhang, a spool carried by the support, a ratchet on said spool, a cord connecting said elbow lift and spool and passing over said sheave, and a stop block carried by the overhang in the path of movement of one louver.
